BASE FOR LIFTING JACKS

David Ashkenas, Middletown, N. Y.

Application June 14, 1934, Serial No. 730,554

4 Claims. (Cl. 254—1)

This invention relates to a portable base for lifting jacks.

It has been my experience that when lifting jacks are used on soft ground that the base of the jack sinks into the ground and sometimes unevenly so that the jack is ineffective to lift the object to which it is being applied.

An object of this invention is to provide a jack base that is so constructed that it may be applied to an ordinarily inaccessible part of the object to which it is being applied by the operator standing at a remote point and so that it may quite easily be pushed into position.

A further object of the invention resides in so constructing the base that it will be prevented from sinking into the ground to an objectionable extent and so that it will maintain a horizontal position.

A further object of the invention resides in the provision of means to removably hold the jack in position and of means to hold a foldable handle in its folded position for storage purposes.

I have found the device admirably adapted for use in elevating automobiles for the changing of tires or other repairs.

I have illustrated one form of the invention but it is to be understood that the invention is not limited to this particular form as it is selected for the purpose of illustration only.

30 In the drawing:

Figure 1 is a perspective view of the device;

Figure 2 is a longitudinal sectional view;

Figure 3 is a transverse sectional view; and

Figure 4 is a view of a modification of the jack

35 holding jaws.

The form of the invention illustrated in the drawing includes a base portion 1 which is shown as rectangular but which may be of any desired form and which is provided with a downwardly extending runner at each longitudinal edge 2, which will facilitate the sliding of the device over rough or soft ground when the device is being put into place.

A foldable handle is attached to the base portion 1 and consists of a stationary section 4 that is secured to the base portion and extends from the rear edge thereof. This section of the handle is U shaped in cross section and is bifurcated at its end. A section 5 is pivoted to the section 4 at 6 and carries at its opposite end an abutment 7. A section 8 of the handle is pivoted to the section 5 at 9 on a pivot that is arranged at right angles to the pivot 6. This section 8 is, in turn, pivoted to a third section 10 at 11 on a pivot that is parallel to the pivot 9. An abut-

ment 12 is carried by the section 10 which, together with the abutment 7, maintains the sections of the handle in alignment when the sections are in their extended positions. The section 10 carries a grip portion 13. It is of course to be understood that the number of handle sections may be increased or decreased as desired.

The depth of the flanges of the stationary section 4 is, preferably, greater than the combined thicknesses of the sections 5, 8 and 10 so that when these sections are folded upon each other and are together folded onto the section 4 the flanges will maintain the folded sections in their folded condition and ready for storage.

In order that the jack may be securely held in position on the base I have provided a pair of gripping jaws 14 that are pivoted to the base at 15 and which are recessed at 16 for the reception of the jack. The free ends of these jaws are normally drawn together by a spring 17 that is attached to the jaws on the side of the pivot remote from the free ends of the jaws.

When it is desired to use the device the jaws 14 are separated and the jack placed between the jaws by which it is held in position on the base 25 ready for use.

The handle of the device having been extended, the base with the jack thereon is pushed into position beneath the object that is to be elevated and the jack may then be operated in the usual manner. The area of the base is such that it will be prevented from sinking into the ground and the runners 2 will prevent the base from slipping to one side or the other.

I have illustrated a modification of the jack 35 holding jaws wherein the jaws 14' are provided with cam faces 15' so that when the jack is forced against the same the jaws will separate and the jack will be permitted to enter the recess between the jaws. Moreover the jaws are provided with abutments 16' against which the jack may be forced with the result that the jaws will be more tightly drawn together. These abutments also act to protect the spring so that it will not be injured by the jack while it is in place on the base.

40 What I claim is:

1. In a device of the class described, a base portion, runners on the longitudinal edges of 50 the base portion, a handle including a section rigid with the base portion and sections foldable on each other and on the rigid section, the rigid section being U shaped in cross section and adapted to house the foldable sections.

2. In a device of the class described, a base portion, and means on the base portion to hold a jack thereon, said means including a pair of jaws pivoted on the base portion and a spring 5 for holding the free ends of the jaws together.
3. In a device of the class described, a base portion, and means on the base portion to hold a jack thereon, said means including a pair of jaws pivoted on the base portion and a spring 10 for holding the free ends of the jaws together

and having cam faces to facilitate the entry of the jack between the jaws.

4. In a device of the class described, a base portion, a handle including a section rigid with the base portion and sections foldable on each other and on the rigid section, the rigid section being U shaped in cross section and adapted to house the foldable sections, and means on the base to hold a jack thereon. 5

DAVID ASHKENAS.
